FLUID COATING MACHINE

John Frederick Smith, Quincy, Mass., assignor to
 Compo Shoe Machinery Corporation, New
 York, N. Y., a corporation of Delaware

Application July 19, 1935, Serial No. 32,156

6 Claims. (Cl. 12—80)

This invention relates to fluid coating apparatus used for the manufacture of foot wear and, more particularly, of a bottom cementing machine for applying cement to the lasting allowance of a lasted upper prior to the affixation of an outsole thereto.

An object of the invention is to provide a fluid coating machine having improved features of construction which is capable of giving enhanced and highly satisfactory performance.

More particularly, objects of the invention are to provide a fluid coating machine which is adapted accurately to deposit a controlled amount of fluid in the form of a ribbon or band on the work which is to be coated, comprising a mechanism for transmitting a fluid, such as cement, from a receptacle to the work, wherein such mechanism is subject to accurate adjustment and control.

Further objects of the invention are to provide a machine which is simple and rugged in construction, positive in its operation and not likely to get out of order.

Other objects of the invention will in part be obvious and will in part appear hereinafter.

The invention accordingly comprises the features of construction, combination of elements, and arrangement of parts, which will be exemplified in the construction hereinafter set forth and the scope of the invention will be indicated in the claims.

For a fuller understanding of the nature and objects of the invention reference should be had to the following detailed description taken in connection with the accompanying drawings, in which:

Fig. 1 is a vertical sectional view taken through a machine embodying the principles of the invention;

Fig. 2 is a sectional view taken substantially along line 2—2 of Fig. 1; and

Fig. 3 is a sectional view taken substantially along line 3—3 of Fig. 1.

Referring more particularly to the drawings, there is shown a fluid coating apparatus comprising a fluid receptacle 10 which is screwed to a spindle 11 which in turn is rotatably mounted in a base or pedestal 12.

Fluid, such as pyroxylin cement, is adapted to be inserted in such receptacle through a filling orifice which is normally kept closed by a cap 13. The fluid is adapted to be conveyed to the applying periphery of an applicator 14 by means of a transfer wheel 15. A forward wall 16 of receptacle 10 is inclined approximately 30° from

the vertical plane and has mounted therein a bushing 17 in which a spindle 18 for the applicator is rotatably mounted. The lower end of such spindle is received in a bearing 19 formed in the receptacle wall. A beveled gear 20 is fixed to spindle 18, as illustrated. The applicator comprises a metallic hub section 21 on which the applicator proper 14 is mounted as a rim. This is preferably made of a rather compressible rubber or the like, either solid or sponge rubber being suitable for the purpose. If desired, a felt or bristle applying surface may be used. The applicator is mounted in inclined position with its lowermost peripheral portion exposed for contact with the work, such as the bottom of a shoe. Such positioning of the applicator enables the operator readily to view the work at the point where the cement is being applied. Except for this exposed portion, the applicator is located 5 interiorly of the receptacle, being covered from above by a hinged cover plate 22 and having its uppermost peripheral portion facing the side face of the transfer wheel 15, which also is mounted in an inclined position so as to lie in a plane parallel with the periphery of the opposed 10 portion of the applicator.

The mounting for the transfer wheel 15 comprises a bushing 23 which also is fixedly located in the inclined forward wall 16 of the receptacle. A shaft 24 is located in this bushing and has a beveled gear 25 fixed to its lower end in position to mesh with the gear 20 of the applicator spindle. The upper end of shaft 24 projects beyond its mounting or bushing 23 and is provided with a key-way 26 into which pins or keys 27 extend. These keys are mounted in an upwardly extending hub 28 of the transfer wheel, so that the latter is compelled to partake of rotation of shaft 24 while being slidably therealong to any chosen adjusted position. A compression spring 29 is located between the end of shaft 24 and a cap 30 at the upper end of hub 28 so as to give the transfer wheel a normal bias away from the applicator 14. An adjusting screw 31 is threaded into a boss 32 provided in the upper 30 wall of the receptacle. A knurled head 33 is provided on the exposed end of the adjacent screw and at its interior end, such screw contacts the cap 30 so as to control the position of the transfer wheel along its shaft in order to regulate the 35 distance between the upper periphery of the applicator and the cement carrying face of the transfer wheel. A sealing device 28' is located 40 interiorly of hub 28 to prevent entry of cement 45 in the bearing parts if the fluid level is raised 50 55

above the hub, as shown in Fig. 1. Preferably, however, the fluid level is kept below this point to assure non-interference with the bearing operation.

5 Means are provided for confining the cement carried by the transfer wheel to a path on the lower face thereof which is in registry with the edge of the applicator. This means comprises a wiper or doctor 34 (Figs. 2 and 3) which is 10 pivotally mounted on a pin 35 inserted slidably in the front wall of the receptacle. A spring 36 normally urges the wiper into contact with the lower face of the transfer wheel. A notch 37 is provided in the wheel brushing face of the 15 doctor so as to permit retention of a band of cement thereon which is properly located to register with the applicator. This notch is sufficiently deep to pass a cement band of maximum desired thickness. A wiper 38 is provided for the 20 rear face of the transfer wheel, being mounted on a pin 39 which is carried in a lug 40 that extends inwardly from a side wall of the receptacle. A spring 41 normally urges this wiper into engagement with such wall. Screws 42 and 43 are carried by the receptacle with their lower ends abutting the upper face of wiper 34 on opposite sides of pin 35 to prevent rotation thereof about the axis of such supporting pin, and a screw 44 similarly abuts the upper face of wiper 38 to prevent 25 rotation thereof in one direction. Rotation of the wiper 38 in the other direction is prevented by an extension 45 which is provided on wiper 34 so as to underlie a corner of wiper 38 and also to engage and scrape the periphery of the 30 transfer wheel.

A motor 46 is hung from receptacle 10 so as to drive, through a suitable reducing gear, a driving wheel 47 which is connected by means of a belt or sprocket chain 48 with a pulley 49 attached 40 to the outer end of a shaft 50, which is rotatably mounted in a portion of the front wall casting 16.

A bevel gear 51 is keyed to the inner end of this shaft in mesh with gear 25 of the transfer wheel shaft. It will thus be seen that operation of the 45 motor is adapted to drive the transfer wheel, and that the applicator by virtue of its driving connection at 20 with the upper portion of the transfer wheel driving gear 25 is also adapted to be rotated with its upper peripheral portion going in the same direction as the upper half of the transfer wheel. The gear ratios are such that the periphery of the applicator 14 and the opposed or registered cement carrying portion of the face of transfer wheel 15 move at the same linear speed.

55 In operation, the transfer wheel 15 is adjusted by means of screw 31 so as to be spaced a pre-determined distance from the upper periphery of the applicator 14, this spacing controlling the thickness of the delivered film of cement. Such 60 adjustment may be visually checked by throwing back the receptacle cover 22 and is also adapted to be indicated on a gauge 52 (Fig. 1) located adjacent the outer end of the adjusting screw. Upon starting the motor, the transfer wheel and 65 the applicator will be driven in the above described manner, the lower part of the wheel dipping into the fluid in the receptacle 10 and carrying a portion thereof through the notch 37 to be deposited upon the applicator. An operator holds the 70 work, such as a lasted shoe, against the exposed lower edge of the applicator by hand, feeding the work around at a speed equal to that of the linear speed of the applicator.

75 It will be seen that there has been provided a

machine which is well suited to fulfil its intended purposes.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim is:

1. A fluid coating machine comprising a fluid receptacle, a driven shaft mounted therein, a fluid transfer wheel rotatable with and slidable along said shaft and having its lower portion dipping into the fluid in said receptacle, a rotatable fluid applicator having its peripheral edge in fluid receiving relation with the upper portion of said wheel, means for driving said applicator, and means for moving and selectively holding said wheel at a determined place along its shaft to control the space between it and said applicator.

2. A fluid coating machine comprising a fluid receptacle, a driven shaft mounted in tilted position in a wall of said receptacle, a fluid transfer wheel rotatable with and slidable along said shaft and having its lower portion dipping into the fluid in said receptacle, a tilted rotatable fluid applicator having its upper peripheral edge in fluid receiving relation with the upper face portion of said wheel, said applicator having its lower peripheral edge exposed for contact with work, such edge having a downwardly facing tilted position, means for driving said applicator, and means for moving and selectively holding said wheel at a determined place along its shaft to control the space between it and said applicator.

3. A fluid coating machine comprising a fluid receptacle, a driven shaft mounted in tilted position in a wall of said receptacle, a fluid transfer wheel rotatable with and slidable along said shaft and having its lower portion dipping into the fluid in said receptacle, a tilted rotatable fluid applicator having its upper peripheral edge in fluid receiving relation with the upper face portion of said wheel, said applicator having its lower peripheral edge exposed for contact with work, such edge having a downwardly facing tilted position, means for driving said applicator, spring means normally urging said wheel away from said applicator, and an adjusting screw for moving said wheel toward said applicator and holding it in determined spaced relation therewith.

4. A fluid coating machine comprising a fluid receptacle, a shaft mounted in tilted position in a wall of said receptacle and extending interiorly thereof, a fluid transfer wheel rotatable with and slidable along said shaft and having its lower portion dipping into the fluid in said receptacle, a tilted applicator shaft located along said receptacle wall, a tilted rotatable fluid applicator having its upper peripheral edge in fluid receiving relation with the upper face portion of said wheel, said applicator having its lower peripheral edge facing in a downwardly facing tilted position, means for adjusting said transfer wheel along its shaft and for selectively holding it in a determined adjusted position to regulate the space between it and said applicator, and wiper means for limiting the cement carried by said transfer wheel to a path located opposite the cement receiving periphery of said applicator.

5. A fluid coating machine comprising a fluid receptacle, an applicator shaft, a transfer wheel shaft perpendicular to said applicator shaft and having a portion extending into said receptacle, 5 a transfer wheel rotatable with and slideable along said inwardly extending shaft portion, a rotatable applicator on said applicator shaft having a peripheral edge a portion of which faces a side face of said transfer wheel and having another portion of said peripheral edge exposed for contact with the work, means for driving said shafts, spring means urging said transfer wheel away from said applicator, and an adjustable abutment for regulating the distance between said 10 wheel and applicator.

6. A fluid coating machine comprising a fluid receptacle having an inclined front wall recessed to provide a gear housing, an applicator shaft rotatably mounted along said wall and having its 15 lower portion extended into said housing, a rotatable applicator at the upper end and a gear at

the lower end of said shaft, a second shaft rotatably mounted in said wall substantially perpendicular to said applicator shaft and having its lower end extending into said housing and its upper end into said receptacle, a gear on said second shaft meshed in driving relation with applicator shaft gear, a transfer wheel rotatable with and slideable along the upper end of said second shaft and having its lower edge dipping into the contents of said receptacle and a side 10 face of its upper portion opposed to the periphery of said applicator, a driving shaft mounted in said wall and having a driving gear meshed in driving relation with the gear on said transfer wheel shaft, and means for driving said driving shaft, said gears being proportioned to drive the periphery of said applicator and the opposed face portion of said transfer wheel at equal linear speeds.

JOHN FREDERICK SMITH. 20
